Mathias Swank

UNITED STATES PATENT OFFICE.

MATTHIAS SWANK, OF PHILADELPHIA, PENNSYLVANIA.

IMPROVEMENT IN RELIEVING STEAM-BOILERS OF CINDERS.

Specification forming part of Letters Patent No. 35,845, dated July 8, 1862.

To all whom it may concern:

Be it known that I, MATTHIAS SWANK, of Philadelphia, in the State of Pennsylvania, have invented a new and improved arrangement whereby combustion-chambers are readily relieved of cinders or ashes; and I do hereby declare that the following is a full and exact description thereof, reference being had to the accompanying drawings, and to the letters of reference marked thereon.

Similar letters in the different views indicate like parts.

My invention relates to steam-boilers; and it consists in connecting the bottom of the interior of the combustion-chamber, or that part of the boiler between the flue-sheet and furnace, with the outer shell of the boiler by means of tubes, which tubes are opened or closed at pleasure by a sliding valve on the exterior of the boiler, whereby the cinders and ashes that collect in the bottom of the combustion-chamber are readily removed; and, I would here remark, the fresh air introduced in operating this valve assists and improves the combustion, although it is no feature of my invention.

In order that those skilled in the art may make and use my invention, I shall proceed to describe its construction and operation.

Figure I represents a sectional elevation. Fig. II, a section through A B; Fig. III, a plan view, enlarged, of valve; and Fig. IV, a section of valve.

In the different views, G represents the boiler; H, the furnace; C, the combustion-chamber; D, the bridge-wall; F, the flue-sheet, all of which parts may be constructed as desired and need no minute description here, since they form no part of my invention.

In Fig. I, C represents the combustion-chamber; K K K K, tubes passing through the water-space E, surrounding the combustion-chamber C, connecting the bottom of the interior of the combustion-chamber C with the exterior of the boiler G, the number and position of the tubes K K K K being governed by the size and construction of the boiler G, the object being, however, to place the said tubes in a position where the cinders and ashes lodge and collect in the chamber C. J represents a sliding valve acting upon the

exterior ends of the tubes K K K K, and is bolted to the boiler. The tubes may be of any size or form.

In explaining my improvement, its advantages, and operation, I would call attention to the fact that steam-boilers made with a bridge-wall D, as in Fig. I, cinders and ashes which are driven over the bridge-wall, accumulating in the bottom of the combustion-chamber C without means of escape, would entirely choke up the flues in sheet F. To avoid this difficulty, boxes, or, as they are termed, "ash boxes" or "pits," have been and are attached or formed underneath; but, being below and out of the current or flow of water, mud and other deposits collect in and fill up the water space surrounding this pit or ash-box, and in consequence thereof the said pit or ash-box burns out in a short time, and this difficulty, however, is avoided by my invention, wherein consists one of its advantages--viz., the tubes K K K K, passing through the water-space E, which is in the direct current or flow of water and offering so little obstruction to the water, and there consequently being no place for the mud or deposit to accumulate, there is nothing to obstruct the supply and immediate contact of water with the parts in contact with the ashes and cinders, and hence those parts can never burn. Besides obviating the above difficulty, the fresh air introduced by operating the sliding valve J assists combustion, and also blows out anything that may have lodged in the flues.

The operation is quite simple. The engineer at pleasure, whether in motion or not, as in the case of a locomotive-boiler, by the lever L operates the sliding valve J, (Fig. III showing the valve open,) when the cinders or ashes fall out. The same end can be attained by making an aperture of most any form where I place the said several tubes without altering my invention; but I use, suggest, and recommend, but do not confine myself to the use of tubes, as they offer less obstruction to the water in water-space E, and also increase the water-surface.

Now, I do not wish to be understood as claiming the tubes K K K K passing through the water-space E, nor improving the com-

bustion by the introduction of fresh air, as these features are described in patents granted to Peter Cooper, October 13, 1831; F. P. Dimpfel, November 30, 1858, and to James E. McConnel for additional improvements, October 6, 1857; but

What I consider novel, claim, and desire to secure by Letters Patent, is—

The combination and arrangement to re-

lieve combustion-chambers of steam-boilers, or that part of the boiler between the furnace and flue-sheet, of ashes or cinders, substantially as represented, and operated for the purpose set forth.

MATTHIAS SWANK.
